CLAIM

The ornamental design for a watch strap, as shown and described.

DESCRIPTION

FIG. 1 is a front view of a watch strap showing my new design;

FIG. 2 is a rear view thereof;

FIG. 3 is a right side view thereof;

FIG. 4 is a left side view thereof;

FIG. 5 is a bottom view thereof;

FIG. 6 is a top view thereof;

FIG. 7 is a perspective view thereof;

FIG. 8 is another perspective view thereof;

FIG. 9 is another front view thereof, showing the watch strap in an alternate configuration;

FIG. 10 is a rear view thereof;

FIG. 11 is another front view thereof, showing the watch strap in an alternate configuration; and,

FIG. 12 is a rear view thereof.
